FABRIC SPREADER

Arthur P. Lewis, New Bedford, Mass., assignor
to The Firestone Tire & Rubber Company,
Akron, Ohio, a corporation of Ohio

Application August 25, 1933, Serial No. 686,746

16 Claims.

This invention relates to fabric spreaders, and more especially it relates to spreading or tentering devices of the roller type adapted to laterally stretch and remove folds and wrinkles from continuous lengths of sheet material passing thereover. The chief objects of the invention are to provide an improved tentering device of the character mentioned, that will be positive in its action; that is of simple and economical construction; and that will not tear or harm the material on which it is operating. Other objects will be manifest in the following specification.

Of the accompanying drawing:

Figure 1 is an end elevation of the improved fabric spreader in inoperative association with sheet material from a supply-roll of the latter; Figure 2 is a side elevation of the device in its preferred form, parts being broken away; Figure 3 is an elevation of one of the units from the end portions of the roll; Figure 4 is a section on the line 4—4 of Figure 3; Figure 5 is a diametric section of one of the units from the medial portion of the roll; Figure 6 is a fragmentary longitudinal section of the device, and the work in engagement therewith; and Figure 7 is a fragmentary side elevation of one end portion of another embodiment of the invention.

Referring to Figure 1 of the drawing, 10 is a roll of sheet material, such as fabric, and 11 is a sheet thereof, the roll 10 being mounted for rotation upon an axial support 12. The improved tentering device, generally designated 13, is a rotatably mounted roller structure that is disposed in proximity to the roll 10 and parallel thereto, said tentering roller being in the path of the sheet 11 as the latter is drawn onto or withdrawn from the roll 10 for laterally stretching said sheet to remove wrinkles and folds therefrom.

As is most clearly shown in Figure 2, the tentering device comprises an axial shaft 15, a series of tentering units 16, 16 positioned in laterally abutting relation centrally of said shaft, and respective series of tentering units 17, 17 of a different type positioned in laterally abutting relation on the shaft at each end of the series of units 16. The end portions of the shaft 15 are formed with journals, and the shaft is mounted in suitable bearings (not shown) in which it freely rotates. Both types of tentering units, 16 and 17, are made of resilient soft rubber composition.

Each tentering unit 16 consists of a unitary

structure comprising a hub portion 16a, a frustoconical, work-engaging portion 16b, and a frustoconical web 16c connecting the hub to the work-engaging portion 16b at the small side of the latter as is most clearly shown in Figure 5. The work-engaging portion 16b is somewhat less in width than the hub 16a, and it overhangs the latter, so that when a plurality of the units are mounted on the shaft 15 their hubs will be in laterally abutting relation and their work-engaging portions will be in spaced relation to each other. The hub 16a is formed with an axial aperture 16d to accommodate the shaft 15, there being sufficient friction between the hub and shaft to cause the unit normally to rotate with the shaft. As is clearly shown in Figure 2, the units 16 on one side of the middle of shaft 15 are reversed as compared to the units on the other side thereof, in each case the taper of the frusto-conical work-engaging portions 16b being toward the middle of the shaft.

Each tentering unit 17 consists of a unitary structure comprising a hub portion 17a, and a plurality of radial arms 17b, 17b integral therewith, each of said arms being generally triangular in shape and connected at one of its corners to the hub 17a, at one side of the latter. The arrangement is such that one side of each arm 17b is flush with a lateral face of the hub, the remainder of the arm being disposed in overhanging relation to the hub and extending slightly beyond the opposite lateral face of the hub, as is most clearly shown in Figure 4. The juncture of each arm 17b with the hub 17a is relatively small, and because of the overhanging arrangement described, the arm is free to flex, about said juncture as a pivot, when radial pressure is applied to the outer face of the arm. The outer face of the arm 17b, which is the face opposite the angle at its juncture with the hub, is somewhat oblique with relation to the axis of the hub, and is serrated as shown at 17c. The hubs 17a are formed with respective axial apertures 17d to accommodate the shaft 15.

The units 17 are mounted upon the shaft 15 at each end of the group of units 16, the oblique, serrated faces of the arms 17b sloping toward the middle of the shaft. A spacing collar 18 may be mounted on shaft 15 between the group of units 16 and each group of units 17. The units 17 are mounted on shaft 15 in determinate angular relation to each other, the arms 17b of each unit being intercalated with relation to the arms of adjacent units. To retain the units 17 in the relation described, the hub 17a of each unit is

formed with a pair of diametrically opposed recesses 17c in one lateral face and a pair of complementally shaped and arranged lugs 17f, 17f on its other lateral face, the lugs of one unit being adapted to fit within the recesses of the adjacent unit to prevent relative angular movement of the units. The units 16, 17 are retained on the shaft 15 by a collar 19 near one end thereof and a washer 20 and nut 21 near the other end thereof, the shaft being locally threaded at 22 to receive said nut. The units 16, 17 may be so tightly clamped between the collar 19 and washer 20 as normally to be incapable of rotary movement with relation to the shaft, although 15 the device will function satisfactorily if they do so move.

The operation of the device is best shown in Figure 6 wherein it will be seen that the sheet material 11, in passing about the tentering roller 13, exerts such pressure upon the work-engaging portions 16b of the units 16 and the arm 17b of units 17 as to move said portions out of their normal positions. Thus the portions 16b are locally deformed and the webs 16c flexed, and the arms 17b are flexed angularly about their narrow juncture with the hubs 17a, the arrangement being such that said flexing results in the moving of the work-engaging surfaces of the units 16, 17 toward the respective ends of the shaft 15.

Because the units 16, 17 are made of rubber, and because of the serrated work-engaging surfaces of the arms 17b, said units have good frictional engagement with the sheet material 11, and the flexing of said units as described, by the sheet material as it passes thereover, causes said units progressively to urge said material laterally each way from its longitudinal center line, with the result that the sheet is smoothed and folds and wrinkles eliminated therefrom. Since the work does not extend completely around the device 13, the tentering units are free to resume their normal positions in that portion of device not in contact with the work. The arrangement of the arms 17b in intercalated relation prevents the marginal portions of the work from being pulled over the free ends of said arms.

The device is of simple and economical construction and is efficient in its operation. When the tentering units become worn or damaged they are easily replaced with new units.

In the embodiment of the invention shown in Figure 7, the tentering units 16 are dispensed with and a solid roll 23 mounted in place thereof.

The device may be otherwise modified without departing from the spirit of the invention or the scope of the appended claims.

What is claimed is:

1. A tentering device for sheet material consisting of a rotatable structure over which said material passes, said structure having a straight axis comprising deformable tentering units that are deformed by said material, said units having rubber edges to contact said material for urging same laterally both ways from its middle by reason of said deformation.

2. A tentering device for sheet material consisting of a rotatable structure over which said material passes, said structure comprising ten-

tering units composed of flexible arms having arcuate edges for engaging said sheet material, which units are so constructed as to be flexed by the sheet material passing thereover and in flexing to urge said sheet material in opposite 5 directions from its middle.

3. A tentering device consisting of a roller structure comprising an axial shaft, a plurality of tentering units in laterally juxtaposed relation on the respective end portions of the shaft, 10 each of said units comprising yielding, overhanging, work-engaging arms, the arms of each unit being intercalated with the arms of an adjacent unit, and means on each unit for preventing relative rotary movement of the units with relation 15 to each other.

4. A tentering device consisting of a roller structure comprising an axial shaft, a plurality of tentering units disposed centrally on said shaft, said units comprising yielding, annular work- 20 engaging portions, and a plurality of tentering units disposed at the respective ends of said first-mentioned units, the last-mentioned units comprising radial, yielding, work-engaging arms.

5. A tentering device consisting of a roller 25 structure comprising an axial shaft, a plurality of tentering units disposed centrally on said shaft, said units comprising yielding, annular work-engaging portions, and a plurality of tentering units disposed at the respective ends of said 30 first-mentioned units, the last-mentioned units comprising radial, yielding, work-engaging arms, the arms of each unit being intercalated with the arms of an adjacent unit.

6. A tentering device consisting of a roller 35 structure comprising a plurality of work-engaging units of resilient material, each of said units comprising a frusto-conical work-engaging portion, a hub portion, and a frusto-conical web connecting said portions. 40

7. A tentering device consisting of a roller structure comprising a plurality of work-engaging units, each of said units comprising an annular work-engaging portion, a hub portion, and a yielding, frusto-conical web connecting said 45 work-engaging portion to said hub portion.

8. A combination as defined in claim 7 in which the hub, web, and work-engaging portions are integral, and the web is connected to one lateral margin of the said work-engaging portion. 50

9. A tentering device consisting of a roller structure comprising a plurality of tentering units, each of said units comprising a hub portion and a plurality of generally, triangular work-engaging arms, said hub portion and arms being integral and composed of resilient material, the arms being attached to the hub at one of their corners. 55

10. A tentering device consisting of a roller 60 structure comprising a plurality of tentering units composed of resilient rubber, each of said units comprising a hub portion, and a plurality of radial arms of generally triangular shape secured to the hub portion at one of their corners, 65 the work-engaging surfaces of the respective arms overhanging one lateral margin of the hub.

ARTHUR P. LEWIS.
